USPC ..... **D25/64****CLAIM**(58) **Field of Classification Search**

The ornamental design for a ladder, as shown and described.

USPC D25/62-69; 182/156, 152, 162, 112,
182/113, 215, 220, 120, 106, 23, 26, 115,
182/129, 201, 207, 103, 245, 2.11, 102,
182/151, 107, 21, 180.1, 194, 130, 132,
182/67.4, 157, 161, 230
CPC ... E06C 5/04; E06C 7/00; E06C 1/383; E06C
7/02; E06C 1/26; E06C 1/28**DESCRIPTION**

See application file for complete search history.

FIG. 1 is a perspective view of a ladder showing our new
design;(56) **References Cited**FIG. 2 is a front view of the ladder shown in FIG. 1;
FIG. 3 is a rear view of the ladder shown in FIG. 1;

U.S. PATENT DOCUMENTS

FIG. 4 is a left side view of the ladder shown in FIG. 1;
FIG. 5 is a right side view of the ladder shown in FIG. 1; and,1,935,349 A 11/1933 Breslow
2,109,886 A 3/1938 Lewis
3,871,481 A 3/1975 Ballek
4,011,926 A 3/1977 Larson et al.FIG. 6 is a top plan view of the ladder shown in FIG. 1.
The broken lines shown in the figures are for the purpose of
illustrating portions of the ladder and form no part of the
claimed design.The evenly spaced broken lines in the drawings are to show
portions of the ladder that form no part of the claimed
design. The dash-dot-dot broken lines define the bounds of
the claimed design and form no part of the claimed design.**1 Claim, 6 Drawing Sheets**|
